UNITED STATES PATENT OFFICE

93,328

DESIGN FOR AN OUTDOOR LAMP FOR A GASOLINE SERVICE STATION

Raymond C. Browe, Newark, N. J., assignor to
Socony-Vacuum Corporation, New York, N. Y.,
a corporation of New York

Application November 25, 1933, Serial No. 49,870

Term of patent 14 years

To all whom it may concern:

Be it known that I, RAYMOND C. BROWE, a citizen of the United States, residing at Newark, in the county of Essex and State of New Jersey, have invented a new, original, and ornamental Design for Outdoor Lamp for Gasoline Service Station, of which the following is a specification, reference being had to the accompanying drawings, forming part thereof, wherein,

Figure 1 shows a side elevational view of the outdoor lamp for a gasoline service station em-

bodying my design the shade thereof having translucent side panels.

Figure 2 shows a top view of the shade portion of the lighting fixture.

Figure 3 shows a sectional view taken on line 3—3 of Fig. 1.

I claim:

The ornamental design for an outdoor lamp for a gasoline service station, as shown.

RAYMOND C. BROWE.
